T. KNIGHT.

LOCK.

APPLICATION FILED JULY 5, 1904. RENEWED JUNE 14, 1907.

916,878.

Patented Mar. 30, 1909.

UNITED STATES PATENT OFFICE.

THOMAS KNIGHT, OF ATLANTA, GEORGIA.

LOCK.

No. 916,878.

Specification of Letters Patent. Patented March 30, 1909.

Application filed July 5, 1904, Serial No. 215,303. Renewed June 14, 1907. Serial No. 378,924.

To all whom it may concern:

Be it known that I, THOMAS KNIGHT, a citizen of the United States, and a resident of Atlanta, in the county of Fulton and 5 State of Georgia, have made a certain new and useful Lock; and I do hereby declare the following to be a full, clear, and exact description of same, such as will enable others skilled in the art to which it appertains 10 to make and use the same, reference being had to the accompanying drawings, and to letters and figures of reference marked thereon, which form a part of this specification.

This invention relates to locks of the class 15 known as combination, being the adaptation thereof in a novel form, to use on cabinet work and doors and the like, the invention consisting of the novel form of lock herein-after set forth.

20 The device is shown in the accompanying drawings as follows:

Figure 1 is an elevation of the device with the front-plate removed showing its interior. Fig. 2 is a central, horizontal section. Fig. 25 3 is a side elevation of the bolt. Fig. 4 is an edge view thereof. Fig. 5 is an illustration of the dial on the front or back plate or both. Fig. 6 is a side elevation of one of the tumblers. Fig. 7 is an edge view of said 30 tumblers. Fig. 8 is a side view of one of the geared tumblers and Fig. 9 is an edge view thereof.

In these figures, like reference characters are uniformly employed in the designation 35 of corresponding elements of construction.

A is the frame or casing and B is the bolt, either of which may be of any desired form of construction so long as the latter is mounted so as to slide in suitable guides and 40 be provided with lugs b which enter the openings provided therefor in the annular flanges in the tumblers as will be now set forth.

C and C¹ are tumblers mounted on and 45 secured so as to revolve with the shafts c and c¹, respectively and D and D¹ are tumblers mounted revolvably upon the said shafts, respectively, although loosely mounted and rotatable independently of said shafts, these 50 latter named tumblers, D and D¹, being provided with gear-teeth completely around their peripheries which intermesh and cause the simultaneous rotation thereof. The shafts c and c¹ are rotatably mounted in the 55 casing, and thereon, in the same plane and near one side-plate are mounted the afore-

said geared tumblers D and D¹ and near their opposite ends, in the same plane and near the other side-plate of the casing, are mounted the tumblers C and C¹. On the 60 inner or contiguous faces of the said tumblers C, C¹, D and D¹, are annular flanges c² and c³ on the tumblers C and C¹, respectively, and d on the tumblers D and D¹. The tumbler C¹, is provided with a hub c⁴ on its side 65 nearest the tumbler D¹ and on the extremity of this hub so as to lie substantially within the plane of the annular flange d of the tumbler D¹ are wings c⁵, extending substantially 70 radially therefrom and within the said 70 flange d of the said tumbler D¹ is a pin d² so set as to be interposed in the path of motion of the said wings c⁵ and cause a temporary engagement between the tumblers C¹ and D¹ and indirectly also with the geared tumbler 75 D. The annular flanges c², c³ and d are provided with notches, the geared-tumblers D and D¹ being so intermeshed that they will both present the said notches on the same 80 side at once and the wings c⁵ of the tumbler C¹ being so placed that when one of the said wings c⁵ is in contact with the pin d² the notch in the annular flange c³ thereon will be 85 out of registry with the notches of the said tumblers D and D¹, or, that is, in such a position that the lug b corresponding may not enter it. The tumbler C is merely, as aforesaid, provided with the annular flange c² and is neither geared nor provided with wings, although said flange thereon is also 90 provided with a notch, said tumbler C moving independently of the others and being the last one necessary to set to complete the opening adjustment of the tumblers.

Obviously no spring is required in this 95 lock but the bolt B is operated in both directions by a knob b¹ or other equivalent device.

A dial E, the pointer e traversing which is secured to the shaft c and another to the 100 shaft c¹, is affixed to the front and back plates of the casing to facilitate setting the combination to open the lock. The said shafts may be provided with knobs c⁶ for operating them. The "combination" may 105 be changed at any time by simply moving the pointers upon their shafts so as to indicate a different line of the graduation when the notches are in proper registry to open.

To open this lock, the knob c⁶ on the shaft 110 c¹ is turned to the left until one of the wings c⁵ comes into contact with the pin d² and then

further until the pointer corresponding shows the desired point on the dial, when the notches in the annular flanges d of both tumblers D and D' will be in the positions 5 shown in Fig. 1, whereupon the rotation of said shaft c^1 is reversed and the pointer brought to another graduation which indicates that the notch in the flange c^2 in tumbler C' is in registry therewith whereupon 10 the other knob, that is, the one on the shaft c is turned in either direction until its pointer shows the right point to bring the notch in the flange c^2 on the tumbler C into registry also, when the bolt may be withdrawn, the 15 lugs b passing freely into the four corresponding notches. An easily opened "day-latch" setting is provided by leaving wheels C , D and D' , in their opening position and simply holding the bolt projected by the use 20 of the tumbler C alone.

Having thus described my invention, what I claim as new and desire to secure by Letters Patent of the United States, is:—

In a lock, a casing and two parallel shafts rotatably journaled therein, two tumblers, 25 one of which is mounted on each shaft to rotate therewith and in substantially the same plane, two intermeshing, geared tumblers one of which is loosely mounted on each of said shafts, means for establishing operative connection between one of said first-named tumblers and the geared tumbler on the same shaft, notched annular flanges on the adjacent faces of all of said tumblers and a bolt mounted in the casing 30 and provided with lugs adapted to enter said notches when in proper relative arrangement.

In testimony whereof, I hereunto set my hand in presence of two subscribing witnesses.

THOMAS KNIGHT.
